UNITED STATES PATENT OFFICE.

FRANK B. COOK, OF CHICAGO, ILLINOIS.

LIGHTNING-ARRESTER.

SPECIFICATION forming part of Letters Patent No. 658,976, dated October 2, 1900.

Application filed February 7, 1900. Serial No. 4,337. (No model.)

To all whom it may concern:

Be it known that I, FRANK B. COOK, a citizen of the United States of America, and a resident of Chicago, Cook county; Illinois, have 5 invented certain new and useful Improvements in Lightning-Arresters, of which the following is a specification.

My invention relates to certain improvements in that class of strong-current protective devices which are clearly described in the 10 patents of Jenks, No. 437,362, dated September 30, 1890, and White, No. 438,788, dated October 21, 1890. This class of apparatus is more particularly designed to protect the instruments of a telegraph or telephone system and persons using the same from the injury which 15 may result from the encroachment of abnormal electric currents of a disruptive character. To accomplish this result, I employ two conducting-plates with their faces held opposed and in close proximity to each other, with a space between them, one or both of said plates having a cavity or recess therein, and a circuit-maker normally held out of a circuit-closing 20 position by means of a mass of non-conducting material disposed in the cavity or recess, which is melted or fused under the influence of the heat created by the abnormal disruptive discharge of the current across or between 25 the plates, whereby the circuit-maker is released to close a circuit between the plates, and thereby divert the dangerous current 30 from the line to the ground or earth.

Reference may now be had to the accompanying drawings for a more particular description of my invention, in which—

Figure 1 is a sectional view and side elevation of the improved arrester. Fig. 2 is a detailed sectional view of the plates with the 40 contact-maker in its normal position held out of circuit-closing position. Fig. 3 is a like view after the melting of the non-conductor by the abnormal current, showing the circuit-maker in circuit-closing position. Fig. 4 is a 45 view of the perforated dielectric.

The carbon plates A A² are held with their opposed faces in close proximity by means of the spring holding members 6 6, between which the pair of carbon plates are forced.

As shown, these holding members 6 6 are mounted upon a suitable base B. A dielectric, as shown at E, having an opening e is

positioned and held between the carbon plates. This dielectric may be of mica, with a single large opening, or of silk, which latter material has a plurality of openings. The plate A² is connected to a ground and the plate A is connected to the line.

I will now describe the means for establishing a conducting-path between the plates under the influence of the heat generated by the encroaching abnormal current.

As shown, the recesses f f are formed, respectively, in each one of the carbon plates A A², within each of which recesses is packed 65 a suitable quantity of wax (designated at h) or other suitable material which will melt into a liquid or approximately-liquid condition under the influence of heat. Embedded within the wax in each of the pockets is a 70 ball of good conducting material, (designated at j.) When by reason of the disruptive discharge across the space between the two carbon plates, and the wax in the recesses is melted, by the heat thus generated these 75 conducting-balls are released and permitted to roll together, by gravity, owing to the shape of the recess, and when together, as they are still in contact with the carbon plates and in contact with each other, they establish a con- 80 ducting-path between the plates, and thus close the line-circuit to earth through the protector.

From the foregoing description it is evident that I provide means whereby a circuit maker 85 or closer or switch is normally withheld from closing the circuit by means of a mass of non-conducting material, which when melted releases the circuit maker or closer, which then assumes a circuit-closing position.

What I claim is—

1. A high-tension arrester, or current-protecting device, consisting of carbon plates held adjacent to each other but separated from one another, a mass of non-conducting 95 material adapted to be melted into a liquid, or semiliquid form and a movable conductor normally held out of contact by the material aforesaid, which conductor is adapted to make contact between the plates when said mate- 100 rial is melted.

2. A high-tension arrester, or current-protective device, consisting of carbon plates held adjacent to each other, but separated

- from one another, a cup-shaped recess or cavity in one or both of the carbon plates, a mass of non-conducting material adapted to be melted into a liquid or semiliquid form, and
- 5 a ball or balls of conducting material, held by the non-conducting material, which when released by the non-conducting material falls by gravity into a position to close the circuit between the plates.
- 10 3. A high-tension arrester, or current-protecting device, consisting of carbon plates held adjacent to each other, but separated from one another, a recess or cavity in one or both of the carbon plates, a mass of non-con-

ducting material adapted to be melted into a liquid or semiliquid state held within the recess or cavity, and a movable contact-maker, normally withheld by the material aforesaid, which is adapted when said material is melted to establish a conducting-path between the carbon plates.

Signed by me at Chicago, Illinois, this 26th day of January, 1900.

FRANK B. COOK.
